UNITED STATES PATENT OFFICE.

ROBERT H. WARREN, OF NEWARK, NEW JERSEY.

DESIGN FOR A STAIR-CARPET BUTTON.

SPECIFICATION forming part of Design No. 24,631, dated August 27, 1895.

Application filed August 1, 1895. Serial No. 557,903. Term of patent 7 years.

To all whom it may concern:

Be it known that I, ROBERT H. WARREN, a citizen of the United States, residing at Newark, in the county of Essex and State of New Jersey, have invented and produced a new and original Design for Stair-Carpet Buttons; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 In the drawings, Figure 1 is a front elevation of the newly-designed button; and Fig. 2 is a section of the same on line *x*, these views being deemed necessary and sufficient to fully illustrate my design.

20 The leading feature of my design consists in the stair-carpet button, square in outline and having a raised center, which is perforated, and around the perforation is displayed ornaments, the axes of which are in lines radiating from the center, and the outer edges of which are beaded.

In the drawings, *a* indicates the button, which is four-sided, the sides and angles being equal. The center of said button is raised, as indicated in Fig. 2, and is perforated, as at 30 *b*, and around this perforation I display a ring-shaped ornament *c*, having radiating arm-shaped ornaments *e*, which extend from the ring-shaped ornament outward to the corners of the button. Between said arm-shaped 35 parts the center of the button is ornamented by conventional scroll and flowers *e* and *f*. Near the edges of the button are lines *g*, which run parallel with said edges, extending from arm to arm, and between said edges and 40 said lines the space is ornamented by a succession of beads *h*.

What I claim is—

The design for a stair-carpet button, substantially as herein shown and described. 45

In testimony that I claim the foregoing I have hereunto set my hand this 25th day of July, 1895.

ROBERT H. WARREN.
